RAOUL ANDRÉ PERSIN, OF VILLIERS LE BEL, FRANCE, ASSIGNOR TO HIMSELF AND
HENRY ANTOINE LEFÉVRE, OF PARIS, FRANCE.

IGNITION-MAGNETO FOR FOUR-CYLINDER INTERNAL-COMBUSTION ENGINES.

1,285,359.

Specification of Letters Patent. Patented Nov. 19, 1918.

Application filed July 25, 1917. Serial No. 182,809.

To all whom it may concern:

Be it known that I, RAOUL ANDRÉ PERSIN, a citizen of the French Republic, residing at Villiers le Bel, Seine et Oise, France, have invented certain new and useful Improvements in Ignition-Magneto for Four-Cylinder Internal-Combustion Engines, of which the following is a specification.

In ignition magneto for internal combustion engines the distributing parts revolve generally at half the speed of the armature, and this arrangement entails a certain amount of complication from a constructional point of view. With the object 10 of remedying this drawback, an arrangement of the winding of the armature has already been proposed in such a manner as to produce in the case of a double T Siemens armature, four sparks per revolution, that 15 is to say, two sparks simultaneously at each 180° of the armature. When the magneto is employed for the purpose of igniting a 4-cylinder engine, in such a case two sparks will be produced simultaneously, namely, 20 one spark in one cylinder during the period of compression, and the other spark in a cylinder during the period of exhaust.

In such an arrangement the two sparking plugs at which these two sparks are 25 simultaneously produced, have hitherto been situated in one and the same secondary circuit, the inlet and outlet of which are connected to two contacts of the distributor and should be completely insulated.

Constructions of that kind have the two 30 following main drawbacks:—

1. From an electrical point of view the two sparks occur in media that oppose different resistances. The spark produced in 35 the cylinder in which compression is taking place, will encounter in the compressed mixture a higher resistance than the spark occurring in the cylinder in which exhaust is taking place. Consequently the former 40 spark which alone serves a useful purpose is weak, whereas the other spark which is of no utility, is a strong spark.

2. From a constructional point of view 45 the insulation of the two ends of the secondary circuit presents various difficulties, more particularly in machines of small size.

The present invention has now for its object to provide an improved apparatus that will remedy the above stated drawbacks.

This improved apparatus is characterized

essentially by the provision of two independent secondary circuits each having its point of departure in the framing of the machine, and feeding respectively the two 50 sparking plugs at which the sparks are to be produced simultaneously.

In these circumstances, these two sparking plugs into which the current is passed simultaneously by the distributor, are fed by two distinct secondary circuits, and the 55 spark produced at each of these plugs will have its maximum intensity.

In the accompanying drawings:—

Figure 1 illustrates by way of example in 60 a diagrammatic manner one way of constructing the improved apparatus according to this invention, and

Fig. 2 illustrates a modification thereof.

In the example of the apparatus illustrated in Fig. 1, the armature has two cores 65 a, b ; the primary circuit c is wound on these two cores and its ends are connected in the usual manner on one hand to the framing d of the machine and on the other hand to an interrupter e of known construction. Each of the cores a, b is wound with a secondary circuit f, g , the ends of which are connected on one hand likewise to the framing d and on the other hand to the two contacts h, i 70 of a distributor j of the usual construction. 75 These contacts in rotating come into contact with the two brushes k, l connected to the two sparking plugs m, n where the sparks are to be produced simultaneously, and with the two brushes o, p connected to 80 the two sparking plugs q, r of the other two cylinders. 85

Fig. 2 shows a modification in which the armature comprises a single core on which are wound the two secondary circuits f, g . 95 The ends of these last two circuits are connected in the same manner as in the preceding example.

The rotary core s on which the contacts 100 h, i are mounted, rotates at the same speed as the armature of the magneto, and these contacts are located in such a manner that at each rupture of the primary circuit, they 105 will be either opposite the brushes k, l or opposite the brushes o, p . Thus for instance in the position shown in the figure, the two sparks will be produced at the two sparking plugs m, n , and when the armature shall have rotated through 180° , the contacts h and i having come into contact with the 110

brushes *o p*, the two sparks will be produced at the two sparking plugs *q r*.

It is to be understood that the constructional details of the improved apparatus 5 may be modified according to the purposes for which it is to be used.

What I claim is:—

In an ignition magneto for a four-cylinder internal combustion engine, a single 10 collector having two contacts 90° apart, a double transformer comprising two separate secondary windings connected respec-

tively to said two contacts and four brushes 90° apart connected respectively to four sparking plugs, said brushes rubbing 15 upon the contacts of the collector.

The foregoing specification of my improvements in ignition magnetos for 4-cylinder internal combustion engines signed by me this 6th day of July, 1917.

RAOUL ANDRÉ PERSIN. [L. S.]
